UNITED STATES PATENT OFFICE.

MATTHEW H. AMES, OF THE UNITED STATES NAVY.

INTERNAL-COMBUSTION ENGINE.

1,069,634.

Specification of Letters Patent. Patented Aug. 12, 1913.

Application filed June 18, 1912. Serial No. 763,518.

To all whom it may concern:

Be it known that I, MATTHEW H. AMES, of the United States Navy, a citizen of the United States, have invented certain new and useful improvements in Internal-Combustion Engines, of which the following is a specification.

The present invention relates to improvements in internal combustion engines, and it has for its object primarily to provide improved valves for engines of this class whereby the operation of the engine and the development of power are more efficient, irrespective of the speed of the engine, the operation of the engine is noiseless or substantially so, and the construction and maintenance of the engine are facilitated. The present invention also enables the valve mechanism of the engine to be fitted in the combustion chamber of the engine cylinder, the novel form and arrangement of the valve ports affording passages of ample size for the inlet of the charge and the exhaust of the products of combustion without rendering it necessary to increase the size of the compression chamber, and in this form of the invention a compact structure is obtained.

The invention consists in certain improvements and combinations and arrangements of parts, all as will be hereinafter more fully described, the novel features being pointed out particularly in the claims at the end of this specification.

In the accompanying drawings, wherein one embodiment of the invention is shown, Figure 1 is a top plan view of an engine cylinder equipped with valve mechanism embodying the present invention; Fig. 2 represents a central vertical section through the upper portion of the cylinder and the valve, the latter in the present instance being contained in the head of said cylinder; Figs. 3 and 4 are perspective views of the outer and inner sleeves or members comprising the valve; and Figs. 5 to 8, inclusive, are diagrammatic views showing the relative positions of the valve sleeves or members for the different phases of the cycle.

Similar parts are designated by the same reference characters in the several figures.

Valves constructed in accordance with the present invention are capable of being applied in different ways to the motors or engines, although, in the most simple and preferred embodiment, the valve is located in the head or compression chamber of the cylinder, and such embodiment is shown in the drawings and will be described hereinafter in detail, the scope of the invention, however, being set forth in the claims.

In the construction shown, the engine cylinder 1, which may be of the usual type, is provided with a flat removable head 2 which serves to close but permits access to the compression and explosion chamber immediately beneath, the usual reciprocating piston 3 operating in the cylinder. The latter in the present instance is provided with adjacently-located inlet and exhaust ports 4 and 5, both of which communicate with the compression and explosion chamber, under the control, however, of a valve which is provided by the present invention. This valve in the embodiment shown comprises two nested or telescoped members, preferably in the form of annular sleeves 6 and 7, the outer of which fits closely within the correspondingly formed wall of the compression chamber of the cylinder, packing rings 8 and 9 being used, if desired or necessary, to prevent leakage of pressure at the ends of the sleeve. The outer sleeve is provided with a pair of angularly-arranged ports 10 and 11 which are adapted to communicate, respectively, with the inlet and exhaust ports of the cylinder when this sleeve is oscillated alternately in reverse directions. The inner sleeve 7 is fitted to revolve within the outer sleeve and packing rings 12 may be used to insure fluid-tight fits at the top and bottom of the sleeves. This inner sleeve is provided with a port 13 which during each revolution of the sleeve communicates alternately and at appropriate intervals with the exhaust and inlet ports of the cylinder. In the present instance, the port 13 of the inner sleeve has

a circumferential length of about one-quarter of the circumference of its sleeve, while the distance between the ports 10 and 11 of the outer sleeve is about equal to one-quarter of the circumference of that sleeve. In order to permit the use of ports of ample size without enlarging the height or size of the combustion and explosion chamber of the cylinder, the ports 10, 11 and 13 of both valve sleeves, and also the inlet and exhaust ports of the cylinder, are inclined or arranged helically, the helical port of the inner sleeve being inclined in the same direction with those in the outer sleeve and the cylinder ports.

In operation, the two-ported sleeve oscillates, while the single-ported sleeve rotates continuously, the latter having a clockwise movement in the present instance, as indicated by the arrow. Different means may be used for suitably operating the valve sleeves, they being provided in the construction shown with telescoped or sleeved shafts 14 and 15 which are connected by the webs 16 and 17 to the respective sleeves. The oscillatory outer sleeve is provided with a crank 18 and the continuously rotating sleeve is operated, for example, by a gear 19 fixed to the shaft or stem thereof and coöperating with a gear 20, the latter being fixed to a suitably journaled shaft 21, which is operatively connected by gearing 22 to a shaft 23. A common timing shaft 24 operating at one-half the engine shaft speed may serve to operate the valve sleeves or members, the shaft 23 being connected thereto by the gearing 25, while an eccentric 26 on the timing shaft operates a pitman 27, which latter is connected to the crank arm 18 for the oscillating valve sleeve.

The operation of the engine on the well-known four-cycle principle may be described briefly as follows: During the suction stroke of the piston which serves to introduce a charge into the cylinder, the port 10 of the oscillating outer sleeve and the port of the continuously revolving inner sleeve register with the inlet port 4 of the cylinder, the exhaust port 5 being then closed, as shown in Fig. 5. During the next in-stroke of the piston which causes compression of the charge, the ports 10 and 13 are both beyond the inlet port 4 and hence this port and also the exhaust port will be closed by the solid portions of the sleeves, as shown in Fig. 6. During the following out-stroke of the piston under the power of the explosion, the inlet and exhaust ports of the cylinder are still closed by the valve sleeves, as shown in Fig. 7, and when this power stroke of the piston has been completed the port 13 of the inner sleeve and also the port 11 of the oscillatory outer

sleeve register with the exhaust port 5 of the cylinder, the consumed gases being exhausted during the following in-stroke of the piston, as shown in Fig. 8, whereupon the ports 10 and 13 again register with the inlet port of the cylinder to introduce a charge for the next cycle.

I claim as my invention:

1. The combination of an engine cylinder provided with inlet and exhaust ports, a piston operative in the cylinder, a valve embodying ported sleeves, coöperative with the ports of the cylinder, and means for oscillating one of said sleeves and for continuously rotating another for controlling said cylinder ports.

2. The combination of an engine cylinder provided with inlet and exhaust ports, a piston operative therein, and a valve embodying a pair of nested sleeves having ports coöperative with those of the cylinder, and means for oscillating one of the sleeves and for continuously rotating the other sleeve to control the cylinder ports.

3. In an internal combustion engine, the combination of a cylinder provided with inlet and exhaust ports and a piston operative therein, a valve embodying a pair of ported members coöperative with the cylinder ports, and means for continuously rotating one of said members and for oscillating the other member to control the cylinder ports.

4. In an internal combustion engine, the combination of a cylinder provided with inlet and exhaust ports communicating with the compression chamber thereof, and having a piston operative therein, a valve embodying nested sleeves mounted in the compression chamber of the cylinder and having ports coöperative with those of the cylinder, and means for revolving one of said sleeves and for oscillating the other sleeve to control the cylinder ports.

5. In an internal combustion engine, the combination of a cylinder provided with inlet and exhaust ports communicating with the compression chamber thereof, and having a piston operative therein, a valve embodying nested sleeves mounted in the compression chamber of the cylinder and having similarly-inclined helically-extending ports coöperative with the cylinder ports, and means for revolving one of the sleeves continuously in one direction and for oscillating the other sleeve alternately in reverse directions to control the cylinder ports.

6. In an internal combustion engine, the combination of a cylinder provided with inlet and exhaust ports, and a piston operative therein, a valve embodying a pair of nested sleeves one having a pair of ports adapted to register alternately with the inlet and exhaust ports of the cylinder, and

the other sleeve having a single port adapted to register alternately with the inlet and exhaust ports of the cylinder, and means for continuously rotating one of said sleeves and 5 oscillating the other sleeve to control the cylinder ports.

In testimony whereof I have hereunto set

my hand in presence of two subscribing witnesses.

MATTHEW H. AMES.
